J. H. BRADNACK

EYELET INSERTING TOOL

Filed Oct. 10, 1923

UNITED STATES PATENT OFFICE.

JOHN H. BRADNACK, OF NEW HAVEN, CONNECTICUT, ASSIGNOR TO THE TUBULAR PRODUCTS COMPANY, OF SOUTHBINGHAM, CONNECTICUT, A CORPORATION.

EYELET-INSERTING TOOL.

Application filed October 10, 1923. Serial No. 667,655.

To all whom it may concern:

Be it known that I, JOHN H. BRADNACK, a citizen of the United States, residing at New Haven, in the county of New Haven 5 and State of Connecticut, have invented certain new and useful Improvements in Eyelet-Inserting Tools, of which the following is a specification.

My invention relates to improvements in 10 eyelet inserting tools, for use in inserting eyelets as a finish or border wall for the openings in pipe or tubing and particularly in tubing having a relatively thin wall, such as is used as conduit for the wiring on automobiles wherein the openings are provided 15 for the passage of the different individual wires, and the object of my improvement is to provide means for cooperating with an eyelet spreader and a punch of substantially 20 ordinary form and involving the use of an upwardly directed stem or neck that is entered into the opening in the eyelet and that projects above the border walls of the opening in the tubing, said means serving to provide 25 a substantially solid and firm backing for sustaining the blow of the punch under conditions of use and also being adapted to be collapsed to drop said stem or neck after the eyelet has been operated upon so as to 30 clear the adjacent walls of the opening and the eyelet and thereby permit of shifting the tubing freely to another position.

In the accompanying drawing:

Figure 1 is a front elevation of part of a 35 punch press of ordinary form and that is equipped with an eyelet inserting tool embodying my invention.

Figure 2 is a side elevation of the tool shown in Fig. 1 on an enlarged scale.

Figure 3 is a plan view of the same.

Figure 4 is a sectional view on the line 4-4 of Fig. 3.

Figure 5 is a sectional view on the line 5-5 of Fig. 3.

Figure 6 is a fragmentary view showing the wedge and adjacent parts in the collapsed position.

Figure 7 is a fragmentary view of a finished eyelet.

Figure 8 is a sectional view on the line 8-8 of Fig. 7.

Figure 9 is an elevational view of the

punch with the socket indicated by broken lines.

My improved eyelet inserting tool 55 comprises means for supporting the eyelet spreader 10 upon the table 11 of a punch press 12, the punch 13 being supported from the ram 14 in the usual manner.

Said spreader 10 and punch 13 are adapted 60 for the insertion of eyelets or eyelet rivets 15 as a finish or border wall for the openings 16 in tubing or pipe 17. The tubing 17 may be of aluminum and used for carrying 65 conducting wires for the wiring systems of automobiles and the openings 16 are provided for the passage of branch or individual wires. Said eyelets comprise a barrel structure 18 that fits within the opening 16 and a rolled flange-like head 19 at the 70 upper end that engages with the outer face of the tubing, and in operating upon said eyelet 15 the lower end portion 20 is rolled over to provide a flange structure for being opposed to the inner face of the tubing. 75 The general structure of the eyelet 15 is curved to correspond to the curvature of the tubing.

The active cooperating faces of the spreader 10 and the punch 13 are of the 80 usual form. Thus the spreader 10 has an upwardly projecting neck or head 21 that is generally of tapered form in cross-section, the side walls merging with a shoulder structure 22 that serves as a seat and guide 85 for the eyelet and that receives the effect of the blow of the punch. The punch 13 has a cavity 23 that is generally the reverse of the opposed structure of the spreader as described and fits thereover, with the eyelet 90 interposed therebetween.

In the position for use the neck or head 21 projects upwardly from the interior of the tubing through the opening 16 so as to be enclosed by the adjacent border wall structure 24 of the tubing 17, and in order to permit of shifting the tubing relatively to the spreader 10 the latter must be dropped to provide the necessary clearance for said neck or head 21.

The structure to be described provides for doing this and also provides a substantially solid or rigid backing or anvil structure for sustaining the blow of the punch.

Said structure, as briefly described, comprises a holder 25 for the spreader 10 that is in the form of a movable structure and means for cooperating therewith for effecting the necessary movement, said means in the present instance being in the form of a wedge 26.

Said holder 25 is supported for swinging movement by one end by means of a pivotal pin 27 and is swung upwardly to the proper operating position by the engagement of the free end portion 28 with the wedge 26, the latter being moved longitudinally and riding along the bottom wall 29 of the tubing 17.

The wedge 26 is provided with a control rod 31 that extends along the inside of the tubing 17 and has the outer end 32 projecting beyond said tubing 17 so as to provide access by suitable operating devices. Said devices comprise a strap-lever 33 that is connected to the outer projecting end 32 that is operatively supported from the frame or base structure 34 in any proper manner.

Said base 34 is a laterally elongated structure and I find it desirable to provide an operating handle 35 adjacent the work. Said handle 35 is mounted on a lever 36 and the latter is operatively connected to the strap-lever 33 by means of a connecting-rod 37.

The spreader holder 25 is pivotally connected by means of the pin 27 mentioned to the inner end of a main bar 38 that is in the form of an elongated structure that fits loosely within the tubing 17 and is rigidly supported by its outer end portion 39. As shown, said outer end portion 39 is entered into a hole 40 in a block 41 that constitutes the adjacent end portion of the base structure 34 and is held in place by means of a set-screw 42.

As a detail, the control rod 31 for the wedge 26 is housed within a groove 43 on the underside of the main rod or bar 38.

The control rod 31 is operatively connected to the strap-lever 33 through the medium of a binder-block 44 through which it extends, being held in place by means of the set-screw 45. A pivotal screw 46 connects the binder-block 44 with the strap-lever 33.

A back-stop and support 47 is provided for the control rod 31 in the form of a strap having an opening for the rod and which may be supported for adjustment from the base. As shown, said back-stop and support 46 is part of a right-angled piece of strap material that has the supporting branch 48 longitudinally directed, said branch 48 having an elongated opening 49 for the set-screw 42 and being held in place by means of a nut 50.

The base 34 is secured to the table 11 in any proper manner, as by means of bolts

entered through suitable holes 51 in the opposed or work-end portion of the base structure 34. Said work-end portion 52 is provided with a deep groove 53 for receiving a main anvil-block 54 that has a semi-circular seat 55 for a bushing 56 that is adapted for the particular work, the parts being positioned relatively one to the other by means of a pin-and-socket structure 57.

The bushing 56 has a semi-circular seat 58 that fits and is adapted to receive the bottom wall 29 of the tubing 17 and thus sustain the blow of the riveting or heading operation.

In use, the spreader holder 25 and the wedge 26 combine to effectively fill the pipe or tubing so that there will be operatively a rigid anvil structure to sustain the effect of the blow of the punch.

The structure shown and described permits of obtaining improved operating results, the work performed therewith being superior to that which is obtained or obtainable by the usual hand methods of operation.

I claim as my invention:—

1. An eyelet inserting tool for use with punch presses comprising a base structure, a bar structure supported by one end from said base structure and having means at the other end for receiving the eyelet-spreader, said other end being in the form of a swinging structure that is connected to the adjacent portion of said bar by means of a hinge connection; and a wedge supported for longitudinal movement adapted to cooperate with the free end portion of said swinging structure.

2. In a combination for inserting eyelet rivets within the border portion of openings in tubing and involving the use of a spreader for the eyelets having a neck for being entered from within the tubing through the opening in the tubing, said spreader having a die surface beneath said neck adapted to flange the inserted end of the eyelet rivet, a holder for said spreader supported for movement generally toward and away from the said border portion, and means for positively moving said holder towards said border portion.

3. In combination, a holder for an eyelet spreader and a wedge adapted to be housed within the interior of a tubing structure, said holder being supported for movement generally transverse to the axis of the tubing structure, said wedge being positioned so as to be interposed between said holder on one side and the opposed wall of said tubing structure on the other side, and said holder being positioned so as to make contact with the opposed wall of the tubing on the side opposite that of said wedge.

4. In combination in mechanism for inserting eyelet rivets as a lining for the

border wall of openings in the peripheral wall of tubing, a spreader having a neck for being entered into the opening from within the tubing, a holder incorporated in 5 the structure of said spreader, a positioning bar operatively connected to one end of said spreader and holder and extending longitudinally outward from said end, the

other end of said spreader and holder being free for limited transverse movement, a 10 wedge for cooperating with said free end, and an operating-rod connected to said wedge and extended in parallelism with said bar.

JOHN H. BRADNACK.
